UNITED STATES PATENT OFFICE.

WILLIAM T. DONNELLY, OF BROOKLYN, NEW YORK.

FLOATING STRUCTURE.

Application filed June 8, 1926. Serial No. 114,399.

The invention relates to floating structures such as ships and other bodies adapted for supporting loads or superstructures upon the water. It has for its object to render such floating structures practically unsinkable and thereby safeguard the lives of passengers, as well as any cargo, which may be carried thereon. A further object of the invention consists in the arrangement whereby, should the hull be penetrated in any manner, water could not pass the filling material employed, and, in fact, the invention contemplates the provision of a positive counter-pressure working against the same. A further object of the invention resides in the arrangement of the mass of filling material to such a height that the pressure exerted thereby at any point within the shell is as great or greater than the pressure of the water at the same point upon the outside of the said shell. The construction is such, moreover, that the shell is relieved of pressure at no excessive increase of dead weight.

To this end, my invention consists of filling substantially the entire shell or hull which is to be used for displacement with individual, hollow, air-tight tanks or boxes and preferably of such form as to leave small intermediate free spaces or voids between them. These spaces, in accordance with my invention, are to be filled with a more or less liquid material and preferably a material which at moderately reduced temperatures will assume the characteristics of a solid; or a material of character similar to liquid hydraulic cement which, after being placed as a liquid material, will change by setting and assume the characteristics of a solid material.

The material so introduced not only fills all the voids, but binds the entire aggregate of boxes or tanks into one solid, rigid mass.

The nature of the invention, however, will best be understood when described in connection with the accompanying drawings, in which:

Figure 1 is a side elevation of a ship with portions of the hull and deck broken away to disclose the interior, and also with portions shown in section.

Figure 2 is a transverse section thru the vessel, taken on the line 2—2, Figure 1, and looking in the direction of the arrows.

Figure 3 is a plan of the vessel with por-

tions of the deck broken away to disclose the manner of locating the buoyancy tanks.

Figures 4 and 5 are fragmentary horizontal sections thru buoyancy tanks and filling material and illustrate different methods of arranging the tanks.

Figure 6 is a vertical section, taken on the line 6—6, Figure 5, and looking in the direction of the arrows.

Figure 7 is a transverse section thru the ship, similar to Figure 2, but showing a modification in the manner of positioning the tanks and also in the deck construction.

Figure 8 is a fragmentary sectional view illustrating the manner of fastening the tanks to the type of deck indicated in Figure 7.

Figure 9 is a fragmentary sectional view illustrating the manner of connecting the tanks to the bottom of the ship.

Referring to the drawings, 10 designates a floating structure as a ship designed to carry passengers, cargo, or both, or to support any desired superstructure which is to be safeguarded against sinking; and the floating structure may be provided with means to propel the same. Or, it may be arranged to be towed, or merely fixed at some convenient water location, all of which is well understood and forms no particular part of the invention. When of the vessel type, as indicated in Figure 1, the floating structure may be equipped with a suitable driving engine 11 as an internal combustion engine which, in turn, rotates a propeller 12 in manner well understood to move said vessel.

In accordance with the invention, as much as possible of the entire hull or shell is to be occupied with hollow, air-tight metallic tanks 13; and the engine 11 is, therefore, provided considerably up in the hull as shown rather than at the bottom as the usual practice. A cabin 14 may be provided for the engine 11 as well as a cabin 15 for the captain of the ship. The deck is intended to be as far as possible clear; but I do not wish to be restricted to the particular arrangement set forth, as various characters of superstructures may be supported by the floating shell or hull 10, the invention contemplating the erection thereon even of permanent living quarters on an appreciable scale, as well as the storage of commodities.

in the provision of suitable warehouses on the floating structure.

I am aware that it has been proposed heretofore to provide against the sinking of a floating structure by means of air-tight hollow tanks, such as the tanks 13; but in accordance with my invention, the unavoidable space between the individual tanks and between these tanks and the interior of the hull are to be filled with a material capable of flowing when introduced and which, by change of temperature or by a setting process, as in the case of hydraulic cement, changes its properties to those of a solid. It is further to be understood that in the process of introducing the filling material and while the same is still in a more or less liquid form, the pressure head or surface of the said material within the hull is carried to such a height in relation to the outside load waterline that the resulting hydrostatic head or pressure within will be equal to or greater than the water pressure without upon equivalent areas, when the floating body is carrying the load for which it is designed. Moreover, it is to be understood that the material used is of such a nature as to protect both the interior of the vessel and the exterior of the tanks or floats contained therein. Suitable material for the purpose is bituminous pitch of such characteristics that it will flow as a semi-liquid at a moderate rise of temperature and set to a firm solid upon cooling to ordinary atmospheric temperature. Portland cement of the usual grade, and generally known as hydraulic cement, is also an excellent material for this purpose.

It is preferred, in locating the tanks in the hull, to set the same into groups as by suitable walls or bulkheads 20; and the arrangement of the tanks may be either in rows of adjacent tanks as indicated in Figure 5 or in rows of staggered tanks as indicated in Figure 4, the latter arrangement affording greater buoyancy space proportionately to the weight of metal employed. Smaller tanks 21 may be included between the larger tanks, the balance of the free space being then filled with the bituminous or other material 22, which material occupies between 4 and 5 per cent of the total space.

The bottom of the tanks may be adapted to conform to the bottom 23 of the ship, Figure 7; or, the tanks may be flat both at the top and bottom, as indicated in Figure 2 of the drawings. In the latter construction, a greater amount of filling material will be required over the ship than in the construction indicated in Figure 7, it being understood that this material may continue over the sides as well and also over the tops of the tanks, as indicated in Figure 2. In the embodiment illustrated in Figure 2, the deck

is formed directly over the upper surface of bituminous material as by providing suitable planking 24 thereover; while in the embodiment illustrated in Figure 7, a layer or covering 25 of concrete is provided directly over the top of the tanks and intermediate filling material, said upper surface of the concrete then providing the deck.

I have found it desirable, also, to anchor a number of tanks along the shell or hull; and this may conveniently be effected, for example, by flattening out the lower end of the smaller type of tanks and then riveting the flattened portion 26 thereof to the frame 27 attached to the frame of the ship, as indicated in Figure 9 of the drawings. In the embodiment illustrated in Figure 7 and in which a concrete covering is provided over the tops of the tanks, I prefer to reinforce this concrete by rods 28 and to anchor the flattened upper ends 29 of certain of the smaller type tanks, as by providing an eye 30 thereon thru which the rods are passed before pouring the concrete, as indicated more clearly in Figure 8 of the drawings. By thus securing certain of the tanks in the aforesaid manner, the same perform all of the functions of a hollow stanchion or column of a ship of ordinary structure, and the rigidity of the hull or shell is further enhanced.

I claim:

1. A floating structure, comprising a shell, a plurality of air-tight buoyancy tanks distributed therein to occupy substantially the entire displacement space of the shell, and a filling material enveloping said tanks to occupy substantially the remaining space between the shell and tanks as well as between individual tanks, said material filling the shell to a height to exclude external liquid through the establishment of a graduated pressure in the interior of the shell equal to or in excess of the pressure outside the same.

2. A floating structure, comprising a shell, a plurality of air-tight buoyancy tanks distributed and held therein, and a filling material, capable of attaining under moderate temperatures a semi-liquid condition, in the voids between said tanks and between said tanks and shell and extending to a height providing a head in excess of the hydrostatic head of the water in which the structure floats.

3. A floating structure, comprising a shell, a plurality of air-tight buoyancy tanks distributed and held therein, certain of said tanks being flattened at their ends and provided with eyes for attachment purposes, a filling material in the voids between said tanks and between said tanks and shell and extending up to the load waterline, a covering of concrete over the tops of said tanks and filling material, and horizontally dis-

posed rods therein passing thru the eyes of the flattened tank ends.

4. A floating structure, comprising a shell, a plurality of air-tight buoyancy tanks distributed and held therein, a filling material in the voids between said tanks and between said tanks and shell and extending up to the load water line, a deck over the tops of said tanks and filling material and a number of the tanks being secured to the bottom and to the said deck to serve both as compression and tension members between the deck and bottom of the floating structure.

5. The method of excluding water from

the interior of a structure floating therein, which consists in filling substantially the entire interior space with air-tight buoyancy members and then introducing in the voids between said members and between the members and said structure a filling material in a liquid condition to produce graduated pressures therein which, when the structure is floating, will be at all points equal to or greater than the pressure from without the structure, said liquid filling material subsequently solidifying.

In testimony whereof I affix my signature.

WILLIAM T. DONNELLY.
